UNITED STATES PATENT OFFICE.

MARTIN PREHN, OF NEW YORK, N. Y., ASSIGNEE OF ONE-HALF TO MARY L. TALBOT,
OF NEW YORK, N. Y.

DISPLAY DEVICE.

Application filed October 22, 1920. Serial No. 418,659.

To all whom it may concern:

Be it known that I, MARTIN PREHN, a citizen of the United States, residing at New York, in the county of New York, State of New York, have invented certain new and useful Improvements in Display Devices; and I do hereby declare the following to be a full, clear, and exact description of the invention, such as will enable others skilled in the art to which it appertains, to make and use the same.

This invention relates to display devices and in particular to devices for advertising goods for sale, particularly goods in package form, and for displaying them on counters and in other conspicuous places about a store. The invention contemplates the provision of an improved device of this character which is neat and attractive in appearance, simple and inexpensive in structure, and readily and conveniently assembled for use. To this end, the invention involves the provision of a display device made from a single or integral piece of sheet material, such as heavy paper, cardboard, metal, or the like. The sheet material is cut, and scored, if necessary, in accordance with the invention, to provide, when assembled for use, a body or back portion from which projects an article-supporting shelf having a brace connected at one end to the shelf, at a point remote from the back, and operatively attached at its other end to the back at a point below the shelf. The device in use is appropriately mounted with the back in an upright position, and the shelf then provides a firm support for the article to be displayed.

In the accompanying drawing, I have illustrated, by way of example, what I now consider to be the best embodiments of the invention. In this drawing,

Fig. 1 is a perspective view of one form of the display device of the invention assembled for use;

Fig. 2 is a plan view of a flat piece of sheet material cut and scored in accordance with the invention to form my improved display device;

Fig. 3 is a sectional elevation of the assembled display device of Fig. 1;

Fig. 4 is a perspective view of a modified form of the display device; and

Fig. 5 is a detail view of a modified feature of the construction.

Referring to Figs. 1, 2 and 3 of the drawing, it will be seen that the display device of the invention is made from a single integral piece of sheet material 6. As indicated in Fig. 2 of the drawing, the sheet 6 is cut along the full lines *a* and is scored (on the back of the sheet) along the dotted lines *b*, *b'* and *b''*. This cutting and scoring of the sheet 6 can be easily effected in one operation with appropriate dies.

In assembling the device for use, the portion 7 is bent outwardly along the scored line *b* and at the same time the portion 8 is bent downwardly and outwardly along the scored line *b'*. The portion 9 is bent outwardly along the scored line *b''*, and the lower end of the portion 8 is placed on the bent-out portion 9. These operations will be clearly understood by reference to Fig. 1 of the drawing which shows the device assembled.

The portion 7, when the device is assembled for use, provides an article-supporting member or shelf, while the portion 8 provides a brace for this shelf, being operatively secured between the shelf and the body portion of the device. The article-supporting shelf is integrally secured to the body portion or back of the device and extends outwardly from the body portion to provide a flat support for the article to be displayed. The brace 8 is integrally connected at one end to the shelf 7 and is operatively attached, through the instrumentality of the tongue or projection 9, at its other or lower end to the body portion of the device.

For supporting certain types of goods, it will be found desirable to have the article-supporting shelf extend rearwardly of the back portion 6 as well as forwardly thereof. This arrangement can be readily secured by providing the portion 7 with extensions 7' on the other side of the scored line *b*. When the article-supporting shelf is folded or bent about the line *b* the extensions 7' will project rearwardly of the body portion 6, as indicated in Fig. 4 of the drawing, and there is thus provided an article-supporting shelf behind as well as in front of the body portion 6 of the device. If desired, the device may be provided with folded out members 10, cut from the body portion 6, for preventing lateral displacement of the article to be displayed.

As illustrated in Fig. 5 of the drawing, the lower end of the brace 8 may have a narrowed portion or tongue 8' adapted to project through a slit in the body portion 6, and the brace may conveniently be operatively attached to the body portion 6 in this manner, instead of in the manner indicated in Figs. 1, 3 and 4.

The device may be supported in any appropriate manner. Thus, in Figs. 1, 3 and 4, I have shown a supporting leg 11 attached to the rear of the device for supporting the device in easel-like fashion. If desired, the device of the invention may be hung on a wall, or supported in a rack, or otherwise suitably supported.

The article-supporting shelf 7 will usually extend outwardly at right angles to the back or base portions 6. However, it is to be understood that the shelf may, if desired, be supported at a different angle with respect to the back. It will, moreover, be understood that the opening in the body portion resulting from the bending outwardly of the shelf 7 may be of different configuration and of greater size, if desired, than the configuration and size of the shelf 7.

As previously mentioned, the display device of the invention can be manufactured from an integral piece of sheet material by a single dieing operation. Before assembling, the entire device is entirely flat, and no thicker than the thickness of the original sheet material. No adhesives or mechanical holding elements are required, and the device is ready for use instantly after the dieing operation. When assembled, the device is strong, steady and artistic and satisfactorily fulfils all the requirements of an advertising and display device. Usually, the body portion of the device will have printed thereon appropriate advertising matter. This printing may be done before or after the dieing operation, since the dieing operation and the elements provided thereby in no manner interfere with the printing.

I claim:

1. A display device comprising sheet material cut and scored to provide integral tongues extending in opposite directions, one of said tongues being connected with the other tongue intermediate the ends thereof

and extending beyond the connected end of said first named tongue whereby when said first named tongue is bent at an angle to the plate and the other of said tongues is bent at an angle to the first named tongue, it will provide a brace between said tongue near its free end and the plate to hold said first named tongue at substantially a right angle to the plate.

2. A display device comprising a planate body portion, an article-supporting shelf integrally connected to said body portion and projecting therefrom, and a brace integrally connected at one end to said shelf at a point remote from the body portion and extending beyond the shelf at the connected end thereof and operatively attached at its other end to the body portion at a point below the shelf.

3. A display device comprising a planate body portion, an article-supporting shelf integrally connected to the body portion and projecting therefrom, a brace integrally connected at one end to said shelf, and a tongue projecting from the body portion and providing a support for the other end of said brace.

4. A display device comprising a body portion, an article-supporting shelf integrally connected to said body portion and projecting therefrom on each side thereof, and a brace integrally connected at one end to said shelf at a point remote from the body portion and operatively attached at its other end to the body portion at a point below the shelf.

5. A display device comprising an integral piece of sheet material cut to provide when assembled an article-supporting shelf projecting from each side of the body portion of the device and supported by a brace extending between the body portion and the shelf.

6. A display device comprising a body portion, an article-supporting shelf projecting outwardly on each side of the body portion, a brace integrally connected at one end to said shelf, and a tongue projecting from the body portion and providing a support for the other end of said brace.

In testimony whereof I affix my signature.

MARTIN PREHN.
